UNITED STATES PATENT OFFICE.

WILLIAM M. WATTIE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

DOBBY CYLINDER.

Application filed March 27, 1926. Serial No. 98,016.

This invention relates to improvements in the cylinder of the well-known Knowles head and it is the principal object of the invention to construct the cylinder of reversible parts so that when the leading tooth of the section of teeth which actuates the vibrator levers becomes worn the section may be reversed to replace the worn tooth in leading position with an unworn tooth.

It is a further object of my invention to provide a cylinder formed in part by a mandrel non-circular in cross section to receive correspondingly formed laminations having a blank and a toothed area the toothed area lying symmetrically with respect to the non-circular portion of the laminations so that when the sections are reversed the toothed section will occupy the same relative angular position with respect to the mandrel.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a vertical section through a portion of the well-known Knowles head of the type shown in patent to Knowles No. 186,350, showing the cylinders made according to my invention,

Fig. 2 is an enlarged section on line 2-2 of Fig. 1,

Fig. 3 is an enlarged side elevation of the cylinder taken in the direction of arrow 3, Fig. 1,

Fig. 4 is a front view of one of the laminations shown in Fig. 3 after the leading tooth of the same has become worn, and

Fig. 5 is a fragmentary view of the lamination shown in Fig. 4 but showing the same reversed with the worn part of the tooth at the finishing end of the section of teeth.

Referring more particularly to the drawings it will be seen that I have provided loom arches 10 having a head frame 11 secured thereto in which is secured a heel pin 12.

50 Vibrator levers 13, one of which is shown in the drawings, are pivoted on the heel pin 12 and there is mounted on each vibrator for limited rotation a vibrator gear 14 pivotally connected as at 15 to one end of a connector 16. The other end of each con-

nector is attached to a harness lever one of which is indicated at 17, said harness lever being pivoted on a pin 18 fixed in the loom frame. The vibrator levers 13 are controlled as to their vertical position by a pattern 60 chain 19 by means of which the vibrator gears 14 are raised or lowered according to the requirements of the pattern or weave. The matter thus far described is of common construction and forms no part of my present invention.

65 The vibrator gears 14 are actuated by upper and lower cylinders 30 and 31, respectively, which form the subject matter of my present invention and inasmuch as both cylinders are alike as far as my present invention is concerned, but one will be described. As shown more particularly in Figs. 2 and 70 3, each cylinder is provided with a mandrel 32 having a flattened portion 33 and having 75 extending therethrough a driving shaft 34 formed with flanges 35 and 36, respectively, lying at the opposite ends of the mandrel and engaging the interior surface thereof. Flange 35 is grooved as at 37 to receive a 80 holding screw 38 threaded through one end of the mandrel and by means of which the mandrel is held in fixed angular relation with respect to the shaft 34.

85 Said mandrel is provided with a shoulder 39 near one end thereof which forms a backing for a series of laminated sections 40 shown more particularly in Figs. 2 and 4. Each of said sections is provided with a blank peripheral area 41 and a toothed area 90 42 and is provided with an opening 43 corresponding in size and shape to the cross-section of that part of the mandrel designed to receive said sections. The laminations are provided with openings 44 to receive tie rods 45 which extend therethrough and also shoulder 39 to hold the laminations or sections 40 securely to the mandrel 32. It will be noted that the toothed area of the laminations and the flattened surface 46 are symmetrical with 95 respect to a diameter which passes through the openings 44.

100 Under normal operation the shaft 34 is driven (by mechanism not shown but similar to that set forth in the aforesaid patent to Knowles) and the cylinders 30 and 31 are rotated constantly in opposite directions as indicated by the arrows in Fig. 1. As shown in said figure the vibrator levers 13 are down so that the vibrator gears 14 are in position 110

to be engaged by the first or advancing tooth 50 of the laminations 40 on the lower cylinder 31. In time this tooth becomes worn to some such a shape as is indicated in Fig. 4. 5 It will be seen that the vibrator gear is provided with a blank space 51 formed by omitting one tooth on the vibrator gear and as the leading tooth of the cylinder becomes worn the teeth thereof will not register correctly 10 with the teeth of the vibrator gear 14. When this condition arises it is necessary merely to reverse the laminations 40, turning them from the position shown in Fig. 4 to that shown in Fig. 5 where it will be seen that the 15 tooth 52 which was formerly the last tooth of the section is now the leading tooth. The surface of the new leading tooth which is now in position to engage the vibrator gear did not have driving connection with the lat- 20 ter before the reversal so that it is as originally formed and the teeth of the cylinder and the vibrator gear will mesh properly. Inasmuch as the toothed section 42 and flattened surface 46 are symmetrically disposed 25 with respect to a diameter passing through the bolt holes 44 and the diameter of the cylinder the laminations may be reversed without disturbing the proper position of the toothed sections.

30 From the foregoing it will be seen that I have provided a multi-part cylinder for the well-known Knowles head so formed that when the leading or vibrator gear engaging tooth becomes worn the sections or laminations may be reversed to present a substantially new and unworn toothed surface to the vibrator gears. While I have shown a comparatively large number of laminations 40 yet it is to be understood that I am not limited to the thickness or number of laminations and I do not wish to be limited to the particular form of driving connection between the shaft 34 and the laminations. Also, it will be seen that the reversal of the 40 parts is permissible because of the fact that the toothed section and the flattened surface on the interior of each of the laminations is symmetrically with respect to a diameter thereof of passing through the bolt holes 44.

45 Having thus described my invention it will be apparent that changes and modifications may be made therein by those skilled in the art without departing from the spirit and scope of the invention, and I do not wish to be limited to the details herein disclosed, but what I claim is:

1. In a loom pattern mechanism having a vibrator lever and a vibrator gear therefor, a cylinder to actuate the vibrator gear, said cylinder having a reversible element thereon a portion of which is provided with teeth to engage the gear and a portion of which is blank, and positive driving connections between the element and the cylinder, the teeth 55 of the element and the driving connection

thereof between the same and the cylinder being symmetrical with respect to a diameter of the element to the end that said element may be reversed on the cylinder and have the toothed section in the same relative angular position with respect to said cylinder and vibrator gear. 70

2. In a loom pattern mechanism having a vibrator lever and a vibrator gear therefor, a cylinder to actuate the gear, said cylinder having a non-circular mandrel, and a plurality of laminations thereon having non-circular openings therein of contour similar to that of the cross-section of the mandrel, each lamination having a portion only of the periphery provided with teeth, the non-circular part of the mandrel and openings and the toothed section being symmetrically disposed about a diameter of the lamination to the end that said lamination may be reversed on the cylinder and have the toothed section in the same relative angular position with respect to said cylinder and vibrator gear. 80

3. In a loom pattern mechanism having a vibrator lever and a vibrator gear therefor, a cylinder to actuate the gear, said cylinder having a rotating mandrel, a series of laminations for the mandrel, each lamination having a portion only of the periphery thereof provided with teeth, and means defining a driving connection between the mandrel and the laminations, said means and the toothed section of the vibrator lying symmetrically with respect to a diameter of the laminations to the end that said lamination may be reversed on the cylinder and have the toothed section in the same relative angular position with respect to said cylinder and vibrator gear. 90

4. In a loom pattern mechanism having a vibrator lever and a vibrator gear therefor, a cylinder for the vibrator gear normally constantly driven in the same direction, a mandrel forming part of the cylinder, a removable element on the mandrel, said element having a section of teeth on a portion only of the periphery thereof, means extending through the element and a portion of the mandrel to hold the element to said mandrel, said means and the toothed section of the element being symmetrical with respect to a diameter of the element to the end that said element may be reversed on the cylinder and have the toothed section in the same relative angular position with respect to said cylinder and vibrator gear. 100

5. In a loom pattern mechanism having a vibrator lever and a vibrator gear therefor, a cylinder for the vibrator gear comprising a mandrel substantially cylindrical in form but having a flattened portion cutting off a portion of the cylindrical surface, a plurality of laminations on the mandrel each having an opening therethrough substantially circular with the exception of a por- 110

- tion which interrupts the circular form of the opening so that said laminations fit snugly on the mandrel, bolts extending parallel to the axis of the cylinder through the
- 6 laminations and a portion of the mandrel, and a section of teeth formed on each lamination extending over a portion only of the periphery of the laminations, the flattened portion of the mandrel and opening in the
- 10 lamination, the section of teeth of the laminations and the bolts all being symmetrical-
ly disposed with respect to a diameter of the laminations, whereby the laminations may be reversed and maintain the same angular re-
15 lation with respect to the cylinder and vi-
brator gear.
6. A cylinder for a loom head motion hav-
ing a vibrator gear, said cylinder comprising
20 a mandrel and a plurality of laminations
thereon, each lamination having teeth ex-
tending around a portion only of the periph-
ery thereof, said laminations being reversible
on the mandrel to assume the same angular
25 position with respect to the mandrel and
vibrator gear as existed before the reversal,
said laminations and central portion having
engaging non-circular portions.
7. A cylinder for a loom head motion
having a vibrator gear, said cylinder com-
20 prising a mandrel partly circular and partly
- non-circular in cross-section, a shoulder
formed integral with the mandrel, a plu-
rality of laminations mounted on the man-
drel, each lamination having a toothed area
and a blank area and each lamination having
35 an opening therethrough having circular and
non-circular portions to fit snugly over the
mandrel, and securing means extending
longitudinally of the cylinder passing
through the laminations and the shoulder.
40
8. A cylinder for a loom head motion hav-
ing a vibrator gear, said cylinder comprising
a mandrel partly circular and partly
non-circular in cross-section, a shoulder
formed integral with the mandrel, a plu-
45 rality of laminations mounted on the man-
drel, each lamination having a toothed area
and a blank area and each lamination hav-
ing an opening therethrough having circu-
lar and non-circular portions to fit snugly
50 over the mandrel, and securing means ex-
tending longitudinally of the cylinder pass-
ing through the laminations and the shoul-
der, the toothed portions of the laminations
and non-circular portion of the mandrel all
55 being symmetrically disposed with respect
to a diameter of the mandrel.

In testimony whereof I have hereunto af-
fixed my signature.

WILLIAM M. WATTIE.
